UNITED STATES PATENT OFFICE.

THOMAS MATHEWS, DECEASED, LATE OF LEICESTER, ENGLAND, BY ANNIE MATHEWS, OF LEICESTER, AND HARRY BUCKINGHAM, OF LONDON, ENGLAND, ADMINISTRATORS.

PAPER AND LIKE TOY.

1,383,836.

Specification of Letters Patent. Patented July 5, 1921.

Application filed November 26, 1920. Serial No. 426,610.

To all whom it may concern:

Be it known that we, ANNIE MATHEWS and HARRY BUCKINGHAM, subjects of the King of Great Britain, residing at Leicester, 5 England, and London, England, respectively, are the duly appointed administrators of the estate of THOMAS MATHEWS, deceased, late a subject of the King of Great Britain, and resident of Leicester, England, 10 the latter having invented certain new and useful Improvements in or Relating to Paper and like Toys, of which the following is a specification, reference being had thereto in the accompanying drawing.

15 This invention relates to toys and the object is to reproduce in toy form what are commonly known as "roundabouts" or "mer-ry-go-rounds".

Roundabouts as generally understood consist of representations or models of horses, 20 termed hobby horses, boat like vehicles, carriages and other devices in which children are seated while the said devices are rotated or revolved in a circle around a central sup- 25 port for amusement.

The object of this invention is to construct a toy roundabout in an inexpensive form 30 largely of cardboard and which can be operated by hand to give the necessary revolv-

ing motion to the horses and other devices. The invention in its broadest sense comprises a circular frame, or canopy or hood resembling an umbrella when opened, 35 formed of cardboard and having centrally disposed externally at its upper part or apex a knob or equivalent which on its underside is bored or socketed to fit rotatably over the upper end of a pole or central support or a pin thereon, the lower end of which support 40 is adapted to enter a socket in a wooden block secured to a circular base plate preferably of cardboard and to be maintained upright thereon.

The canopy at its lower end all around has 45 a flattened edge from which the horses, cars or like devices are suspended by wire or like rods the ends of which are fashioned into a form for clipping or gripping at one end on to the said flattened edge and at the other 50 end on to the figure or device (horses, cars or the like) to be suspended therefrom.

The toy is set in motion by gripping the knob at the top of the canopy between the finger and thumb and by imparting a twist-

ing motion thereto similar to that necessary 55 for spinning a top, whereby the suspended figures are caused to revolve around the central support.

A convenient constructional form of the invention is shown by way of example in the 60 accompanying drawing wherein:

Figure 1 is a perspective view of the toy in assembled form for use.

Fig. 2 is a plan of the same.

Fig. 3 is a vertical section thereof.

Fig. 4 shows one of the suspending rods.

Figs. 1 and 2 are drawn to a smaller scale than Figs. 3 and 4.

In the illustrated embodiment, a flat circular base 1 of cardboard has fastened centrally upon it a circular block 2 of wood or other suitable material provided with a central hole 3 into which the lower end of a wooden support 4 tightly fits so as to stand upright at the top. The support 4 has a metal 70 pin 5 upon which a canopy 6 is adapted to rotate. This canopy is provided at its apex with a knob 7 and has around its periphery a flat ring or annular flange 8 upon the inside and outside edges of which the bent 75 coiled ends 9 of wire rods 10 are adapted to fit. The lower ends 11 of the rods 10 are coiled to engage and support figures 12 and devices such as 13 which are respectively cut out and made of cardboard suitably printed, 80 preferably on both sides. The figures 12 are flat and each is suspended by a separate rod 10. The devices 13 are made by cutting and folding the cardboard and each device is suspended by two rods. Obviously the number 85 and character of the figures and devices may be varied.

A convenient method of forming the canopy 6 consists in taking a blank or piece of cardboard and scoring it in lines radiating from a center and bending it along the scored lines and joining the two ends together which will form a canopy consisting of segments of triangular form as shown much resembling an umbrella. The apices 100 of the sections are cut off before the ends of the latter are united, which leaves an opening at the top of the canopy. A flat cardboard plate or cap 14 of polygonal shape is affixed over this opening and the edges of 105 the said cap are scored and bent down to form flaps 15 which are glued or otherwise secured to the sections of the canopy. On

the top of the cap 14 the wooden knob 7 is affixed by glue or tacks and the cap is perforated in alinement with a socket in the underside of the knob which fits over the 5 aforesaid pin 5.

The lower edge of the canopy is provided with a horizontal extension 16 formed by scoring the lower edge of each segment of the canopy and turning it outward to form a 10 flap to which is secured the beforementioned flat ring 8. The said ring 8 is attached to the extension 16 so that both its internal and external edges are free to be engaged by the rods 10 as shown in Fig. 3.

15 The ends 9 and 11 of the wire rods 10 are each formed into two or more coils of close formation so that the ring 8 and the cardboard figures and devices can be forced between the coils and thereby held in position.

20 All the parts of the toy constructed as shown and described are detachable. That is to say the canopy 6 is removable from the support 4, the latter is removable from the block 2, the wire rods 10 are detachable 25 from the ring 8, and the figures 12 and devices 13 are detachable from the rods. The whole toy can therefore be taken to pieces and contained within a comparatively small box for storing and transport purposes.

30 What we claim then is:—

1. A toy roundabout comprising a circular canopy provided with a socketed knob at the apex thereof, a central support upon the upper end of which the socketed knob of the 35 canopy rotatably fits, a base to maintain said support in an upright position, a flattened edge around the lower edge of the canopy, a series of cut out figures and devices, and rods adapted to detachably engage the aforesaid flattened edge and said figures and devices to suspend the latter from the canopy.

2. A toy roundabout comprising a circular canopy provided with a socketed knob 45 at the apex thereof, a central support, a pin in the upper end of the latter upon which the socketed knob fits to permit rotation of the canopy, a base to maintain said support in an upright position, a flattened edge around

the lower edge of the canopy, a series of cut 50 out figures and devices, and wire rods adapted to detachably engage the aforesaid flattened edge and said figures and devices to support the latter from the canopy.

3. A toy roundabout comprising a circular canopy provided at its apex with a socketed knob, a central support upon the upper end of which said socketed knob rotatably fits, a base to maintain said support in an upright position, a flat annular ring on the 60 lower edge of the canopy, a series of cut out figures and devices, and rods adapted to detachably engage both the interior and exterior edge of said ring and also engage the figures and devices for the purpose of suspending the latter from the canopy, substantially as described.

4. A toy roundabout comprising a circular conical canopy provided at its apex with a socketed knob and having around its lower 70 edge a flat annular ring, a central support having in its upper end a pin upon which the socketed knob of the canopy rotatably fits, a base into which said support detachably fits and is maintained in an upright 75 position, a series of cut out figures and devices, and a series of wire rods having at one end a coil adapted to fit detachably upon the interior and exterior edges of the annular ring and at the other end a coil adapted to 80 fit detachably upon the figures and devices to support same from the canopy substantially as described.

In testimony whereof we affix our signatures in presence of two witnesses.

ANNIE MATHEWS,
HARRY BUCKINGHAM,
*Administrators of the estate of Thomas
Mathews, deceased.*

Witnesses to the signature of Annie Mathews:

R. W. C. TAYLOR,
GEORGE LESTER.

Witnesses to the signature of Harry Buckingham:
